US00D896297S

(12) **United States Design Patent** (10) Patent No.: **US D896,297 S**
(45) Date of Patent: **** Sep. 15, 2020**

(54) **CAMERA**

- (71) Applicant: **Hanwha Techwin Co., Ltd.**,
Seongnam-si (KR)
- (72) Inventors: **Ho Jin Park**, Seongnam-si (KR); **Mun Jun Park**, Seongnam-si (KR)
- (73) Assignee: **HANWHA TECHWIN CO., LTD.**,
Seongnam-si (KR)

(**) Term: **15 Years**

(21) Appl. No.: **29/675,155**

(22) Filed: **Dec. 28, 2018**

(30) **Foreign Application Priority Data**

Jul. 24, 2018 (KR) 30-2018-0034186

(57)

CLAIM

The ornamental design for a camera, as shown and described.

DESCRIPTION

FIG. 1 is a perspective view of a camera showing the new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines shown in the drawings depict portions of the camera that form no part of the claimed design.

1 Claim, 7 Drawing Sheets
